UNITED STATES PATENT OFFICE.

BEN BURELL JOHNSON, OF EVANSVILLE, INDIANA.

SEWER-TRAP.

1,222,296.

Specification of Letters Patent. Patented Apr. 10, 1917

Application filed April 21, 1915. Serial No. 22,902.

To all whom it may concern:

Be it known that I, BEN BURELL JOHNSON, citizen of the United States of America, residing at 606 Cherry street, in Evansville, 5 Vanderburg county, Indiana, have invented certain new and useful Improvements in Sewer-Traps, of which the following is a specification.

This invention relates to sewer traps and particularly to means for preventing back flow of fluid from the sewer through the sewer trap to the place drained by the sewer trap, the said invention being shown as applied to receive fluid from a street gutter 15 and the mechanism being adapted to prevent back flow of fluid to the street level.

A further object of this invention is to provide a sewer trap having means by which the inflowing liquid may not be obstructed 20 while, at the same time, providing means for closing the inlet passage should the pressure within the trap exceed the pressure of fluid running into the trap.

A still further object of this invention is 25 to provide a sewer trap operated by gravity to close the inlet and novel means detachably connected to the sewer box for supporting inclosing medium, the said parts being readily removed for renewing worn or impaired 30 parts or for the purpose of gaining access to the interior of the box.

With the foregoing and other objects in view, the invention consists in the details of construction and in the arrangement and 35 combination of parts to be hereinafter more fully set forth and claimed.

In describing the invention in detail, reference will be had to the accompanying drawings forming part of this specification, 40 wherein like characters denote corresponding parts in the several views, and in which—

Figure I illustrates a vertical sectional view of a sewer box and the masonry in which it is embedded;

Fig. II illustrates a sectional view on the line 2—2 of Fig. I.

In these drawings A denotes a surface plate having an aperture therein, the said plate having a depending flange B' forming 50 a seat for an apertured cover B constituting a vent for the trap. The plate A rests on suitable masonry C which may be concrete or other material for containing and supporting the sewer box J. The sewer box has 55 an aperture into which the pipe D extends and the said pipe D is a conduit for the pas-

sage of fluid into the trap. The pipe D is surrounded within the trap by a chute D' having a flange D² the said flange being secured to the sewer box by fastenings M, such as rivets or the like. On the upper portion of the chute, I mount the brackets G, said brackets having lugs I, constituting bearings for the pins H, which pins extend through lugs H' on the arms K, of the door F, the said door having a handle L, by which it is manipulated. The position of the supports of the arms K is slightly rearwardly of the end of the chute and the lower wall of the chute extends outwardly slightly beyond a vertical line along the end of the upper portion of the chute. This relation of parts is maintained for the reason that the door is to be operated by gravity to close the chute and any back pressure or flow of fluid from the sewer would aid in maintaining the door in such closed position, whereas the door would be free to swing open under pressure of fluid flowing into and through the chute.

The sewer box has an outlet N with a pipe O leading into the sewer, the said pipe O extending through the masonry C, as shown in Fig. I. The door F has a gasket F² which bears against the end of the chute, thereby making a tight joint and insuring against flow of fluid through the opening guarded by the door.

I claim—

1. A sewer box comprising an inclosing wall of masonry, a discharge pipe leading therefrom, a delivery pipe leading thereto, a chute embracing the delivery end of the delivery pipe, means for securing the chute to the said wall, supporting members detachably connected to the chute, said supporting members having rearwardly inclined bearing surfaces, a door for closing the chute, said door having slotted arms to receive the supporting members, and members on the said arms engaging the said supporting members constituting a hinge.

2. A sewer box comprising an inclosing wall of masonry, a discharge pipe leading therefrom, a delivery pipe leading thereto, a chute embracing the delivery end of the delivery pipe and having its outer end beveled with its lower edge extending beyond the upper edge forming an inclined seat for a door, means for securing the chute to the said wall, supporting members detachably connected to the chute, said supporting members having rearwardly inclined bearing sur-

faces, a door for closing the chute, said door having relatively long slotted arms to receive the supporting members, and members on the said arms engaging the said supporting members constituting a hinge for the door.

In testimony whereof, I affix my signature in the presence of two witnesses.

BEN BUREELL JOHNSON.

Witnesses:

Wm. B. MAIN,
JENNY M. MELVIN.
